CLAIM

The ornamental design for a nasal cannula and tubing assembly, as shown.

DESCRIPTION

FIG. 1 is a front perspective view of a first embodiment for a nasal cannula and tubing assembly, showing our new design;

FIG. 2 is a rear perspective view thereof;

FIG. 3 is a top view thereof;

FIG. 4 is a bottom view thereof;

FIG. 5 is a front view thereof;

FIG. 6 is a back view thereof;

FIG. 7 right side view thereof, the left side view is a mirror image of the right side view;

FIG. 8 is a front perspective view of a second embodiment for a nasal cannula and tubing assembly;

FIG. 9 is a rear perspective view thereof;

FIG. 10 is a top view thereof;

FIG. 11 is a bottom view thereof;

FIG. 12 is a front view thereof;

FIG. 13 is a back view thereof; and,

FIG. 14 right side view thereof, the left side view is a mirror image of the right side view.

1 Claim, 12 Drawing Sheets
